UNITED STATES PATENT OFFICE.

FRANK D. FREDETTE, OF NEW YORK, N. Y.

GOLF BAG.

Application filed March 24, 1926. Serial No. 97,127.

This invention relates to improvements in golf bags.

The primary object of the invention resides in the provision of a golf bag which is constructed of metal or other relatively rigid material so as to withstand rough usage without showing the effects, as it will be appreciated that the type of golf bags now in use are usually constructed of flexible material such as leather, canvas or the like and are not capable of long life for the reason that the weight of the golf clubs and other paraphernalia carried therein tends to cause sagging of the bag, thus disfiguring the shape of the same.

Another object of the invention is to provide a novel means for detachably mounting an outer covering of water-proof material to the body of the bag to protect the body from wear and to lend to the bag an artistic appearance. The covering may be of various attractive colors and readily removed or replaced when worn, so that the bag may always be kept in a neat condition, thus eliminating the expense of a new bag when the covering becomes soiled.

A further object is to provide a golf bag in one end of which is arranged a golf ball compartment for carrying of the balls and into which compartment the handles of the "wooden" clubs extend while the shorter or "iron" clubs rest upon the bottom of the bag. This arrangement permits the heads of the clubs to extend an even distance from the open end of the bag so that a suitable cover may be passed thereover to snugly hold the clubs therein.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of my improved golf bag.

Figure 2 is a vertical longitudinal sectional view therethrough.

Figure 3 is a detail horizontal sectional view on the line 3—3 of Figure 1.

Figure 4 is a sectional perspective view showing the manner of attaching the outer covering to the body of the bag.

Referring more particularly to the drawing, the reference numeral 10 designates a

hollow tubular member constructed of a rigid and light material such as aluminum, and which is open at its top as at 11 for the insertion of the golf clubs to be carried thereby, while the opposite end of the member is internally screw threaded as at 12 for the reception of a removable screw cap 13. The interior of the tubular member is divided adjacent the bottom thereof by a partition 14, which has a central opening 15 therein. The partition 14 and cap 13 coact to provide a golf ball compartment 16, in which a supply of golf balls may be carried.

The exterior walls of the tubular member 10 are reduced in diameter for the major portion of its length as at 17 and which reduced portion is provided with a longitudinally disposed recess 18 in which is seated a female element 19, constructed of flat springy metal and which element has its longitudinal edges rolled to provide yieldable portions 20. The portions 20 are normally spaced from the walls of the recess to allow them to be slightly expanded for the purpose to be presently described.

A covering of flexible waterproof material 21 surrounds the reduced portion of the member 10 and is of such thickness as to lie within the plane of the upper walls of the member. The flexible material 21 may be of various colors so as to impart an attractive appearance to the bag, and yet serve to protect the same. The meeting edges of the flexible material are overlapped and are clamped by means of a male element 22, which is in the form of a strip of springy material having its longitudinal edges bent over as at 23. After the meeting edges of the flexible material have been brought together, the male element 22 is pressed into engagement with the yieldable portion 20 of the female element which causes the portions 20 to expand and allows the male element to seat within the recess and be held therein by the portions 20. When the two elements are in co-acting position, the overlapping ends of the flexible material are securely clamped which holds the flexible covering in a taut condition about the bag. The covering is prevented from longitudinal movement by means of the shoulders formed by the reduced portion 17.

A carrying handle or grip 24 is formed on the member 10 adjacent the top thereof

while the top end of the member is reduced as at 25 to receive any suitable cover which may be applied thereto for housing the club ends of the golf clubs.

By providing the opening 15 in the partition 14, it will be seen that the handles of the long clubs, namely those known as the "wood" clubs are passed through the opening and rest upon the cap 13, while the shorter clubs known as the "iron" clubs rest upon the partition 14, so that the heads of the clubs project an even distance beyond the open end of the bag.

From the foregoing description, it will be seen that I have provided a golf bag which is constructed of a rigid material and which is so constructed as to simulate the ordinary style of bag now used for carrying golf sticks in the playing of the game of golf. By constructing a bag in this manner it is possible to always keep the same in a neat and attractive condition.

What is claimed as new is:—

1. A golf bag comprising a hollow rigid member, an outer flexible covering, and co-acting means for removably holding said covering about said hollow rigid member, said co-acting means including a part carried by the outer wall of said hollow member and countersunk below the exterior surface thereof, the meeting edges of said flexible covering overlapping each other, and a removable part engageable with said first part for clamping the meeting edges of said covering therebetween.

2. A golf bag comprising a hollow rigid member having a reduced exterior portion, a flexible covering of waterproof material encircling said reduced portion, and co-acting means for clamping and concealing the meeting edges of said covering for holding the same in a taut condition about said hollow rigid member.

3. A golf bag comprising a hollow rigid member having a reduced exterior portion, a flexible covering of waterproof material encircling said reduced portion, and co-acting means for clamping and concealing the meeting edges of said covering for holding the same in a taut condition about said hollow rigid member, said co-acting means including a female element carried by said hollow member and extending the length of said reduced portion, and a removable male element engageable therewith.

4. A golf bag comprising a metallic hollow member open at the top end thereof, a partition within said hollow member adjacent the bottom thereof, and a removable cap at the bottom of said hollow member and co-acting with said partition to provide a golf ball compartment within said hollow member, said partition having an opening therein for the extension therethrough of the handles of certain golf clubs so as to rest against said cap.

In testimony whereof I have affixed my signature.

FRANK D. FREDETTE.
